CLAIM

The ornamental design for pedestal connector mounting holes, as shown and described.

DESCRIPTION

FIG. 1 is a top perspective view of pedestal connector mounting holes showing my new design;

FIG. 2 is a top view thereof;

FIG. 3 is a bottom view thereof;

FIG. 4 is a bottom perspective view thereof;

FIG. 5 is a top perspective view thereof, showing a typical usage configuration;

FIG. 6 is a top view thereof; and,

FIG. 7 is a side view thereof.

The broken line portions of the figures show unclaimed subject matter only and form no part of the claimed design.
